UNITED STATES PATENT OFFICE.

NEWTON W. BUCH, OF NEW CASTLE, PENNSYLVANIA, ASSIGNOR TO SAFETY ARMORITE CONDUIT COMPANY, OF PITTSBURGH, PENNSYLVANIA, A CORPORATION OF PENNSYLVANIA.

METHOD AND APPARATUS FOR ELECTROPLATING PIPES AND OTHER ARTICLES OF MAGNETIC MATERIAL.

1,168,280.

Specification of Letters Patent.

Patented Jan. 18, 1916.

Application filed June 23, 1913. Serial No. 775,250.

To all whom it may concern:

Be it known that I, NEWTON W. BUCH, a citizen of the United States, residing at New Castle, Lawrence county, Pennsylvania, have invented a new and useful Improvement in Methods and Apparatus for Electroplating Pipes and other Articles of Magnetic Material, of which the following is a full, clear, and exact description, reference being had to the accompanying drawings, forming part of this specification, in which:—

Figure 1 is a plan view of one form of apparatus embodying my invention; and Figs. 2 and 3 are sections on the line II—II and III—III respectively of Fig. 1.

My invention has relation to a novel method and apparatus for electroplating pipes and other articles of magnetic material, and is designed to provide a method and means whereby such articles can be conveniently and rapidly coated and electroplated.

In carrying out my invention, I provide a magnetic lifting frame, which is adapted to simultaneously engage and pick up the ends of a plurality of pipes or other articles to be electroplated. This frame forms means whereby a group of such articles may be simultaneously placed and held within the plating bath and removed therefrom when the plating operation is completed. In the construction shown in the drawing, this lifting frame is composed of a plurality of parallel bars 2 of magnetic material, and each forming a pole piece for a series of electric magnets 3 secured thereto. These bars are arranged side by side in parallel spaced relation, and are connected by suitable cross-bars 4. The ends of the bars 2 are preferably recessed so as to fit the sides of the tank or vessel 6 which contains the electroplating bath. Placed upon the upper edge of one side of this vessel is a bus-bar 7, forming the cathode bus-bar of the apparatus, and which has the multiple circuit connections 8. The ends of the bars 2 when the lifting frame is in position on the tank, rest directly upon the upper surface of this bus-bar 7. Placed upon the upper edge of the opposite wall of the vessel is an anode bus-bar 9 having the multiple circuit connections 10.

11 designate a series of anode carrying bars, which are placed intermediate adjacent bars 2, and which rest directly at one end 55 upon the anode carrying bar 9. At their other ends these bars 11 rest upon but are insulated from the bus-bar 7. The bars 2 also rest upon but are insulated from the bus-bar 9, as indicated at 12. Each bar 11 60 carries a series of depending anode members 11a. The bars 2 may, if desired, be provided on their under side with projections 13, which act to center the pipes or tubes in the manner shown in Fig. 2, where 65 the apparatus is used for electroplating pipes or tubes as distinguished from solid pieces.

The operation is as follows:—The articles to be electroplated are first placed on end in 70 spaced relation in suitable racks or supporting devices. The lifting frame is then brought over the upper ends of these articles, and by means of any suitable crane apparatus, and is lowered into engagement there- 75 with. The bars 2 being energized by the magnets 3, the series of articles will be simultaneously lifted out of the rack; and the lifting frame with the suspended articles is then moved over the tank 6 and the 80 frame is lowered down onto the tank to the position shown in Fig. 2. After the completion of the electroplating operation, the frame is lifted, thereby withdrawing the entire series of pipes or other articles in the 85 bath. By deenergizing the magnets 3, these articles may be dropped at any desired place.

The advantages of my invention will be apparent to those skilled in the art, since it provides a method and apparatus of simple 90 and convenient character by means of which a large number of articles can be simultaneously handled and held within the coating bath during the operation. The pole pieces of the lifting frame and magnets form the 95 cathode members of the apparatus, and these can be readily placed in position upon and removed from the tank without disturbing the anodes.

It will be noted that the pipes or other 100 articles may be coated throughout their entire length inasmuch as there is no mechanical gripper or holder employed. Furthermore, they are held in proper spaced rela-

tion and hence are properly arranged in relation to the electrodes.

I do not, however, limit myself to the particular construction and arrangement of the apparatus which I have herein shown and described, as it will be obvious that various changes can be made in the details of construction and arrangement of the parts without departing from the spirit and scope 10 of my invention as defined in the appended claims.

I claim:—

1. The method of coating articles, consisting in stacking a plurality of articles in pre-15 arranged spaced-apart relation, simultaneously engaging said articles by their upper end surfaces only and in spaced relation by a lifting device, lowering them into a coating 20 bath while so supported and coating them, and then lifting the frame containing the spaced-apart articles out of the bath; substantially as described.

2. The herein described method of coating magnetizable articles, which consists in stacking a plurality of the articles in pre-25 arranged position, bringing a lifting frame having magnetized portions over the articles and causing them to adhere to the said magnetized portions, moving said articles while 30 suspended on said frame over and into the bath and coating them, and then lifting the frame to remove the coated articles from the bath and cutting off the magnetizing force applied to said frame to release the articles; 35 substantially as described.

3. In electro-plating apparatus, a tank, a magnetizable holder for the articles to be coated, means for magnetizing said holder, and means on the holder for spacing the articles in definite positions while suspended 40 from the magnetizable holder; substantially as described.

4. The herein described method of electro-45 plating magnetizable articles, which consists in stacking a plurality of the articles in prearranged position, bringing a lifting frame having magnetized portions over the articles and causing them to adhere to the said magnetized portions, moving said articles while 50 suspended on said frame over and into the bath, and utilizing the said magnetizable portions as cathode members; substantially as described.

5. Apparatus for electroplating, comprising a tank or vessel adapted to contain an 55 electrode, a frame having a plurality of cathode members and adapted to be removably supported on the tank, means for magnetizing said cathode members to cause them to magnetically support the articles to be 60 electroplated, and means for connecting said members with one side of an electric current while on the tank; substantially as described.

6. Apparatus for electroplating, comprising a tank having a series of anode-carrying members supported across the top of said tank, and a lifting frame adapted to be removably supported on the tank, said frame having a plurality of cathode members 70 adapted to fit between the anode members, means for supplying current to the cathode members while on the tank, and means for magnetizing said cathode members; substantially as described. 75

7. Electroplating apparatus, comprising a tank or vessel for the electrolyte, a series of spaced anode-supporting members having anodes depending within the tank, an article supporting and transferring frame comprising a plurality of connected cathode members, a plurality of magnets of which said members form the pole pieces, and means for effecting electrical connections with said pole pieces when the lifting frame is in operative relation to the tank; substantially as described. 80

8. Electroplating apparatus, comprising a movable cathode member, means for magnetizing said member to enable it to magnetically support the articles to be plated, and means for supplying electric current to 85 said member; substantially as described.

9. In electroplating apparatus, a magnetized cathode support having a magnet arranged to hold the articles magnetically within the bath, and means for supplying current to said members; substantially as described. 95

In testimony whereof, I have hereunto set 100 my hand.

NEWTON W. BUCH.
